UNITED STATES PATENT OFFICE.

LEONARD ATWOOD, OF BOSTON, MASSACHUSETTS.

INTERNAL-COMBUSTION ENGINE.

Application filed August 27, 1920, Serial No. 406,330. Renewed May 5, 1922. Serial No. 558,798.

To all whom it may concern:

Be it known that I, LEONARD ATWOOD, a citizen of the United States, and a resident of Boston, in the county of Suffolk and 5 Commonwealth of Massachusetts, have invented certain new and useful Improvements in Internal-Combustion Engines, of which the following is a full, clear, and exact specification.

10 My invention relates especially to internal combustion engines of the two-cycle type, but may be applied to three cycle or four cycle engines, and has for its object the effecting of novel means for delivering 15 liquid fuel thereto; to a new method of lubricating the cylinder; to improve means for packing the piston against leakage, and to general improvements in details of construction hereinafter set forth.

20 In carrying out these important improvements, I omit the packing rings customarily applied about the piston, and introduce packing rings into the cylinder instead at points close above the lower end of the 25 piston when the latter is at the upper extremity of its stroke. Further, the liquid fuel which is preferably low grade oil, is forced through the wall of the cylinder in the vicinity of these packing rings, and the 30 section of the cylinder above these rings being larger in diameter than the piston, this oil attaches to the rising surface of the piston and is carried upward into the influence of the hot combustion chamber, 35 where it is exploded by the hot walls and drives the piston down again. The cylinder is lubricated by the splashing of oil in the crank case, the excess on the piston's outer surface being removed by a wiping 40 ring.

In the drawings forming part of this specification, Fig. 1 is a central sectional elevation of an internal combustion engine made in accordance with my invention. 45 Fig. 2 is a horizontal section on the dotted line 2-2 in Fig. 1. Fig. 3 is an elevation of the piston alone. Fig. 4 is an elevation 50 of the inner combustion chamber. Fig. 5 is an elevation of the outer jacket of the combustion chamber. Fig. 6 is an elevation of the lower section of the cylinder. Fig. 7 is a sectional detail view on a larger scale of the packing rings, showing the oil feeding means.

55 As shown in Fig. 1, the piston 1 is of

substantially well known form, designed to be operatively connected with the crank shaft 2 by a pitman in the customary manner engaging the crank 3, the latter being located in the crank case 4. The cylinder 60 comprises three sections, the lower section 5 being attached to the crank case 4, the outer shell 6 being attached to the section 5, and the inner section or combustion chamber 7 being introduced within and attached 65 to the shell 6.

For heating the combustion chamber 7 sufficiently to ignite the charge for the initial operation of the engine, an annular space 9 is formed between this chamber and 70 the shell 6, into which space the flame from a torch can be thrown through the inlet 10 and thence through said space to the exit 11. To make sure that the heat shall strike through to the upper portion of the 75 combustion chamber in order to make that part the source of ignition, I thin the wall thereat, making preferably three different steps and degrees of thickness, 12, 13 and 14.

It should be observed that the bore of the combustion chamber 7 is larger than the diameter of the piston and that the piston is not provided with packing rings. On the contrary, it is the combustion chamber which 85 is thus made to prevent the passage of the exploding gases, interiorly pressing rings 15, 16 being inserted within an annular space at the lower end of the chamber 7. These rings are held in place by a retaining annulus 17 secured in place against the 90 end of the chamber by suitable screws 19, and are provided with a brass circular wall 20 pressed radially inward by screws 21, as shown in Fig. 7.

95 Preferably the central ring 16 is formed with a groove 22 adjacent the brass wall 20 and extending for its entire periphery, and either this or the lower ring 15 is notched as at 23 to enable the heavy fuel oil to pass 100 from the supply pipe 24 through the hole 25 to the groove 22, and thence to the surfaces of the rings adjacent to the piston. Here, the oil issuing in minute quantities from between the rings, is wiped therefrom by 105 the surface of the piston as the latter rises, until, when the piston reaches its maximum height at approximately a tenth of an inch from the chamber head 26.

110 Acted upon both by the heat of the pis-

ton and especially by the heat of the chamber 7, this film of oil adhering by its viscosity to the entire surface of the piston is instantly vaporized, and when the piston 5 reaches the end of its up-stroke, the joint compression and heat ignites the charge and forces the piston downward.

When the piston reaches the end of its down stroke, which is the position illustrated in Fig. 1, its upper end does not sink below the uppermost ring 15, but several longitudinally disposed channels 27 which are formed in the upper section of the piston provide the means for the discharge of the exhaust gases to the annular space 28 between the adjacent ends of the combustion chamber 7 and the cylinder section 5, and thence through the exhaust pipe 29. Simultaneously therewith a blast of air enters from the opposite side, being conveyed through a pipe 30 from within the crank case 4 where the air is compressed by the descent of the piston. By means of this inrush of air, the exhaust gases are practically all expelled from the combustion chamber and the latter filled with the oxygen required for the proper intermixture with the oil-vapor to give perfect combustion.

When the piston rises under the inertia of its fly-wheel, a supply of fresh air is drawn in through the intake valve 31.

In addition to the oil in the crank case, I prefer to provide another supply for the lubrication of the piston at a point substantially midway of the height of the cylinder-section 5, such as the oil cup 32 connected with the cylinder by a pipe 33. Hence by means of one or both, the piston is thoroughly lubricated, a groove 34 near the lower end of the piston aiding in carrying the oil up to the wiping ring 35 which, by its clasping pressure about the piston keeps any excess of oil from passing to a point where it can be reached by the exhaust.

45. What I claim is:

1. An internal combustion engine comprising a cylindrical combustion chamber, an elongated piston loosely fitting the same and reciprocative therein, and an exhaust passage below the lower end of said combustion chamber, and packing rings carried by said chamber close above its lower end in contact with said piston, the bottom stroke of said piston presenting its top surface slightly above said packing rings, and said piston having a plurality of channels descending from its top surface to communi-

cate with said exhaust passage when in its lowest position.

2. An internal combustion engine comprising two cylinders of substantially equal interior diameters secured in alinement with a space between for the escape of the exhaust, the upper cylinder having a head and being the combustion chamber, a piston reciprocative in said cylinders, the upper cylinder having means for the admission of fuel oil just above its lower end, means for lubricating said piston when in the lower cylinder, and means for removing the lubricating oil from its surface just before the latter receives the fuel oil.

3. An internal combustion engine comprising a three-part cylinder, one cylinder having a head and being the combustion chamber, a second cylinder being of substantially equal diameter with the combustion chamber and held in alinement therewith but spaced therefrom to form an exhaust passage, and the third cylinder surrounding the larger part of the first-named cylinder and attached thereto and to the second cylinder, and a piston fitting loosely in the first cylinder and fitting gas-tight in the second cylinder and reciprocative therein.

4. An internal combustion engine comprising a combustion chamber, a shell surrounding the same and partially spaced therefrom to form an annular heater space, an inlet to said space and an outlet therefrom diametrically opposite to the inlet to permit flame entering said inlet to traverse entirely about the combustion chamber to said outlet, a piston reciprocative in said combustion chamber, and means for applying a film of fuel oil to the surface of said piston as it rises in said combustion chamber.

5. An internal combustion engine comprising a combustion chamber having its cylindrical wall thinnest near its upper part, a shell surrounding said chamber and having openings to permit flame to circulate through the space formed between said thin portion and said shell, a piston reciprocative in said chamber, and means for applying a film of fuel oil to the surface of said piston as it rises into said chamber.

In testimony that I claim the foregoing invention, I have hereunto set my hand this 11th day of August, 1920.

LEONARD ATWOOD.
